Paul Van Moé
By Louis J. Paine, Jr.
ATTORNEY

UNITED STATES PATENT OFFICE.

PAUL VAN MOÉ, OF ROUEN, FRANCE.

BLOTTING-PAD MOUNTING.

Application filed October 3, 1922. Serial No. 592,164.

To all whom it may concern:

Be it known that I, PAUL VAN MOÉ, citizen of the Republic of France, residing at Rouen, France, post-office address 23 Place 5 de l'Hotel de Ville, have invented certain new and useful Improvements in Blotting-Pad Mountings, of which the following is a specification.

In order to make my invention more clearly understood, I have illustrated, as an example, an embodiment thereof in and by the appended drawing, wherein:

Figure 1 is a longitudinal axial section of my blotting pad.

Figure 2 is a cross section of the tightening plate of my blotting pad.

Figure 3 is a plan view of the clamping washer for the T-shaped assembling piece of my device.

Figures 4 and 5 are detail views showing the bolt of the pad closing device.

Figure 6 is a cross-section of Figure 4, looking toward the square head of the bolt.

Figure 7 is a fragmental plan view of 25 the holder plate.

As shown, my blotting pad mounting is constituted by a variably sized plate 6 made of metal or any other suitable material, the side edges of which are bent down as at 10, 30 Figure 2. On said plate 6, which is provided with a hole 6' at its center, is riveted a collar 4 provided with a flanged lower end 4'. On this collar is slidably and rotatably fitted the neck 12 of a knob 5, the upper

35 part 5' of which is in the form of a hinged cap or cover, said knob being made of metal or of any other suitable material. The knob and collar conjointly constitute a handle, and the center of the said cap is formed 40 with a depressed rectangular seat or opening 3' to receive the square head 3 of a bolt 2. Inside the handle I arrange a coil spring 11 of suitable size, the lower part of which rests on plate 6 while its upper part bears 45 against the cap 5' of knob 5.

Having positioned this spring, I introduce bolt 2 through aperture 3', the cylindrical end of which bolt is threaded. Said threaded end goes through the hole 6' in plate 6. 50 I then exert on knob 5 sufficient pressure to properly set spring 11. I then screw on the threaded part of the bolt a cross-piece or shoe 1 and secure it by means of a pin as shown at 9, Figure 4.

55 Washer 7, which may be of any shape, is secured by any suitable means to the wooden

sole 13, a rectangular aperture 8 being made in the said washer to register with shoe 1, and a recess 13' being formed in the upper surface of said sole. 60

In order to secure the blotting paper strips on the above described mounting, it is only necessary to fit them against wooden sole 13, turning up their ends 14 and 15, then to place thereon plate 6 with its connected parts, the shoe 1 of bolt 2 corresponding with the rectangular hole 8 of washer 7, then to exert a pressure on knob 5 to force shoe 1 through aperture 8 into recess 13' and to rotate the knob one quarter of a turn, said recess being of such size and shape as to permit this movement of shoe 1 therein. Pressure on knob 5 is then discontinued and the shoe occupying the position shown by dotted lines 16, Figure 3, maintains the two 70 parts 6 and 7 in connected relation, with the blotting paper strips locked between them. 75

My mounting allows worn or soiled blotting paper strips to be properly replaced and does away with the screw hitherto used to 80 lock blotting pads.

It should be understood that I do not intend to be limited to the embodiment hereinbefore described as an example, but desire to reserve my right to alter the constructional details as well as the sizes thereof so far as can be reasonably claimed without departing from the principle and scope of my invention as hereinafter claimed. 85

Having now particularly described and 90 ascertained the nature of my said invention as well as the manner in which the same is to be performed, what I claim is:

1. A blotter, comprising, in combination, 95 a sole adapted to carry the blotting paper and having a recess in its upper face; a clamping member secured on said face and provided with an aperture which is disposed directly above said recess; a plate adapted to hold the blotting paper against the sole 100 and provided with an opening alining with said aperture and recess; a handle secured to said plate; a fastening bolt attached to said handle and projecting at its lower end through said plate opening, said bolt end being provided with a locking shoe which is adapted to be inserted through said aperture into said recess and thereafter turned 105 into a position to prevent its withdrawal through the aperture; and spring means associated with said handle for yieldingly holding said shoe in its turned position in 110

direct engagement with the underface of the clamping member.

2. In a blotter, the combination of a sole adapted to carry the blotting paper; a plate for holding the blotting paper in place thereon; a handle comprising two inter-engaged members, one affixed to said plate and the other rotatably related to and guided by the first one; and a coupling between said plate and sole comprising a member carried by the sole, and a coacting member carried by the rotatable handle member and detachably engaged with the sole-carried member.

3. In a blotter, the combination of a sole adapted to carry the blotting paper; a plate for holding the blotting paper in place thereon; a handle attached to said plate and comprising an upstanding collar fixed to the plate and a spring-pressed knob mounted on said collar for both rotation and axial sliding movement; and a coupling between said plate and sole comprising a member carried by the sole, and a coacting member carried by said knob and detachably engaged with the sole-carried member.

4. In a blotter, the combination of a sole adapted to carry the blotting paper; a plate for holding the blotting paper in place thereon; a handle comprising two inter-engaged members, one affixed to said plate and the other rotatably related to and guided by the first one; and a coupling between said plate and sole comprising a clamping plate carried by the sole, and a bolt carried by the rotatable handle member and detachably engaged with said clamping plate.

5. In a blotter, the combination of a sole adapted to carry the blotting paper; a plate for holding the blotting paper in place thereon; a handle attached to said plate and comprising an upstanding collar fixed to the plate and a spring-pressed knob mounted on said collar for both rotation and axial sliding movement; and a coupling between said plate and sole comprising clamping plate carried by the sole, and a bolt carried by said knob and detachably engaged with said clamping plate.

6. A blotter, comprising, in combination, a sole adapted to carry the blotting paper and having a recess in its upper face; a clamping member secured on said face and provided with an aperture which is disposed directly above said recess; a plate adapted to hold the blotting paper against the sole and provided with an opening alining with said aperture and recess; a handle secured to said plate and embodying a slideable and rotatable hollow knob; a fastening bolt carried by said knob and projecting at its lower end through said plate opening, said bolt end being provided with a locking shoe adapted to be inserted through said aperture into said recess and then turned by the rotation of the knob into a position to prevent its withdrawal through the aperture; and a spring within said knob acting against the same to yieldingly hold said shoe in its turned position.

In testimony whereof I affix my signature.

PAUL VAN MOÉ
